United States Patent Office.

MARTIN LANDENBERGER, OF PHILADELPHIA, PENNSYLVANIA.

Design No. 4,221, dated July 12, 1870.

DESIGN FOR A KNIT SKATING-CAP.

The Schedule referred to in these Letters Patent and making part of the same.

To all whom it may concern:

Be it known that I, MARTIN LANDENBERGER, of Philadelphia, in the county of Philadelphia, and in the State of Pennsylvania, have invented certain new and useful Design for Knit Skating-Cap; and do hereby declare that the following is a full, clear, and exact description thereof, reference being had to the accompanying drawing and to the letters of reference marked thereon, making a part of this specification.

The nature of my design is fully represented in the accompanying photographic illustration, and consists in a "fancy knit skating-cap," made all in one piece, knitted by machinery in various fancy and plain stitches, and in any desired colors.

It is formed by first knitting the band A for the head of very stiff or closely-knitted work.

The crown B is produced by making the fabric more expanded and elastic at that point, to stretch wider than the band A.

The center of the cap C is produced by a closely and compactly-knitted fabric.

The border stitches of this band C are gathered together as tightly as possible to form the center of the crown.

The ornamentation of the cap by ear-tabs, ribbon, trimming, &c., can be varied.

Claim.

The design for a skating-cap, consisting of the striped and compactly fabricated band A, tuffed and loosely-knitted crown B, and closely-knitted tip portion C, all substantially as shown and described.

In testimony that I claim the foregoing, I have hereunto set my hand this 30th day of May, 1870.

MARTIN LANDENBERGER.
